UNITED STATES PATENT OFFICE.

ENOCH JOHN ROGERS, OF MEMPHIS, MICHIGAN.

HARROW.

SPECIFICATION forming part of Letters Patent No. 324,168, dated August 11, 1885.

Application filed May 2, 1885. (No model.)

To all whom it may concern:

Be it known that I, ENOCH JOHN ROGERS, a citizen of the United States, and a resident of Memphis, in the county of Macomb and 5 State of Michigan, have invented certain new and useful Improvements in Harrows; and I do hereby declare that the following is a full, clear, and exact description of the invention, which will enable others skilled in the art to which it 10 appertains to make and use the same, reference being had to the accompanying drawings, which form a part of this specification, and in which—

Figure 1 is a perspective view of my improved harrow, showing the same in position for operation. Fig. 2 is a perspective view of one of the holders for attaching the teeth to the harrow-bars at the points at which the latter cross each other. Fig. 3 is a horizontal sectional view of the said holder. Fig. 4 is a vertical transverse sectional view taken on the line xx in Fig. 3. Fig. 5 is a perspective view of one of the single tooth-holders. Fig. 6 is a horizontal sectional view of the latter, and Fig. 7 is a vertical sectional view taken 25 on the line yy in Fig. 6.

The same letters refer to the same parts in all the figures.

This invention relates to that class of harrows which are constructed wholly of iron; and it consists in certain improvements in the construction of the same, having for their object to provide a device which shall possess superior advantages in point of simplicity, 30 durability, and general efficiency.

With these ends in view the invention consists in the improved construction and arrangement of parts, which will be hereinafter fully described, and particularly pointed out 35 in the claims.

In the drawings hereto annexed, A A designate the front sections of my improved harrow, and B B are the rear sections of the same, which latter are connected with the front sections by means of links C C, while the front sections are connected by chains D D with the draw-bar E. The rear ends of the rear sections are also connected with each other by means of chains F F, so that all of the sections 40 of the harrow shall have the greatest possible freedom of motion.

In lieu of constructing the harrow-sections of single iron bars, as is commonly done, the sections of my improved harrow are made up of links G, each consisting of two parallel bars, H H. The links of the front sections are closed at both ends, while those of the rear sections are only closed at their front ends. Both ends of the rear sections are connected by means of cross-bars, and only the front 55 ends of the front sections are so connected, thus saving one cross-bar for each front section, and at the same time a greater degree of elasticity is thus secured than if extra cross-bars were used. The ends of these links are 60 readily connected by the links C C, and they will also be found convenient for the attachment of the connecting-chains, as herein described. At the points where the links G G cross each other they are connected by means 70 of the clips I, illustrated in Figs. 2, 3, and 4 of the drawings. These clips consist of metallic blocks having transverse openings J and K, one above the other, as shown, and at any desired angle to each other, for the passage of 75 the upper and lower links respectively. The said clip is also provided with a vertical opening, L, through which the tapering tooth M may be driven, the inner sides of the bars H, forming the upper link, being provided with 80 notches N for the accommodation of the edges of the tooth. When the latter is driven into place it spreads the bars H, forcing the links somewhat apart, causing them to bind tightly in the clip, which therefore serves to connect 85 the bars of the harrow-section, and also to connect the teeth to the latter.

For the purpose of attaching the teeth at points where the links or bars G G do not cross each other, I employ the clips or holders shown in Figs. 5, 6, and 7 of the drawings, which are provided only with a transverse opening for the passage of the link and a vertical perforation for the passage of the tooth, as shown, respectively, at O and P. When 90 the tooth is driven it forces the sides of the link apart, thus causing the parts to bind firmly together.

From the foregoing description, taken in connection with the drawings hereto annexed, 95 the operation and advantages of this invention will be readily understood.

The construction is simple and inexpensive. It may be made fully as light as when the harrow-sections are made up of single bars, and the parts may be joined more firmly and durably than when single bars are used.

Having thus described my invention, I claim and desire to secure by Letters Patent of the United States—

1. In a harrow, the combination, with a cross-beam, of a series of front sections secured thereto, the front ends of said sections being connected by a cross-bar and the rear ends disconnected, and a series of rear sections connected at their front and rear portions by cross-bars and connected at their rear portions to each other and at their front portions to the front sections, all of said sections being provided with a number of clips and teeth, substantially as and for the purpose set forth.
2. In a harrow, the combination, with a

cross-beam, of a series of front sections secured thereto, each of said sections being composed of links consisting of parallel bars closed at both ends and secured together by means of cross-bars at their front ends, a series of rear sections composed of links consisting of parallel bars closed at their front ends and secured together at their front and rear portions by cross-bars, all of said sections being provided with clips and teeth, and links for connecting said sections, substantially as and for the purpose set forth.

In testimony that I claim the foregoing as my own I have hereunto affixed my signature in presence of two witnesses.

ENOCH JOHN ROGERS.
